REVERSIBLE TUBULAR LOCK MECHANISM

Frederic K. Heyer, Stamford, Conn., assignor to
 The Yale & Towne Manufacturing Company,
 Stamford, Conn., a corporation of Connecticut

Application May 13, 1949, Serial No. 92,983

14 Claims. (Cl. 292—245)

1

This invention relates to a lock, and more particularly, to a lock of the tubular type. Locks of this class usually comprise a housing, that I shall term a spindle housing, inserted through a transverse bore in a door. A second bore is formed running inwardly from the edge of the door toward the first bore, and in this second bore there is mounted what I term a latchbolt housing. Suitable means are provided within the spindle housing for operating means carried by the latchbolt housing for retracting the latchbolt of the housing and for controlling its operation.

It is an important object of my invention to contribute, in a lock of the class described, lock mechanism that is rendered operative when the spindle housing is assembled to the latchbolt housing in reversed positions in a door, all without requiring the assembly of the operating means in the spindle housing to the operating means in the latchbolt housing. Thus, the assembly of the latchbolt housing to the spindle housing by the mere placing of these housings in proper position relatively to one another, renders the latchbolt retracting mechanism operative regardless of whether or not the latchbolt housing is in either of reversed positions relatively to the spindle housing.

More particularly, by my invention the latchbolt housing thus can be operatively assembled relatively to the spindle housing, without assembly of other operating means, because of the novel relationship between the knob operated latchbolt retracting mechanism mounted in the spindle housing, and the latchbolt and its mechanism mounted in the latchbolt housing.

This feature of my invention results particularly from the utilization of a member in the spindle housing that effects retraction of the latchbolt regardless of the relative positions in which the housings are assembled. I prefer to construct this member as a single plate-like spindle, and I arrange this plate-like spindle to be juxtaposed to a latchbolt retractor in the latchbolt housing in any assembled position of the housings. The knobs of the lock move the plate-like spindle when rotated in one direction or the other, and the plate-like spindle pushes the latchbolt retractor inwardly of the latchbolt housing to retract the latchbolt. While enabling me to assemble the lock in different reversed positions, my extremely novel construction is also adapted very readily for use as an outside door lock, or for bathroom or bedroom operation, as will presently be made quite clear.

2

I have thus outlined rather broadly the more important features of my invention in order that the detailed description thereof that follows may be better understood, and in order that my contribution to the art may be better appreciated. There are, of course, additional features of my invention that will be described hereinafter and which will form the subject of the claims appended hereto. Those skilled in the art will appreciate that the conception on which my disclosure is based may readily be utilized as a basis for the designing of other structures for carrying out the several purposes of my invention. It is important, therefore, that the claims to be granted me shall be of sufficient breadth to prevent the appropriation of my invention by those skilled in the art.

Referring now to the drawings, Fig. 1 is a horizontal sectional view through the lock of my invention showing it applied to a door. Figs. 2, 3, 4, and 5 are sections taken respectively along lines 2—2, 3—3, 4—4, and 5—5 of Fig. 1. Fig. 6 is a view of the lock parts shown in Fig. 1, but with the push button pressed inwardly to locking position and the spindle detent moved thereby to locked position. Fig. 7 is a section in smaller scale similar to Fig. 5, showing the manner in which the latchbolt retractor is actuated by the spindle. Fig. 8 is an end view of a part termed by me a dog actuator, while Fig. 9 is a side view thereof. Fig. 10 is a perspective view of the dog actuator cut in half. Figs. 11 and 12 are views illustrating the movement of a part of the lock effected by the dog actuator.

Fig. 13 is an exploded view of certain of the parts of my invention showing their coaction and operation. Fig. 14 is an exploded view of the spindle plate and spindle detent and the parts utilized in connection therewith. Fig. 15 is an elevation of the spindle housing showing the inside and outside knobs and roses assembled thereto. Fig. 16 is a view looking downwardly on the parts of Fig. 15 with the latchbolt housing assembled to the spindle housing. Figs. 17, 18 and 19 show three assembly relationships between the latchbolt housing and spindle housing, these being in addition to the assembly relationship of Fig. 16. Fig. 20 is an elevation of the latchbolt housing and the latchbolt and retractor associated therewith. Fig. 21 illustrates a modified form of the invention adapted for bathroom operation.

Referring now more particularly to the drawings, and more especially to Figs. 1, 15, 16, and 20, the latchbolt housing of my invention is des-

ignated generally by reference letter L and comprises a front portion 10 through which projects a latchbolt 11 adapted to be retracted by a retractor 12. The spindle housing is designated by reference letter S in Fig. 15 and is formed of two parts, one of which is designated by reference numeral 13 and the other by reference numeral 14. The parts 13, 14 are threaded so that roses 15 and 16 may be applied thereto, it being the function of the roses to secure the spindle housing relatively to the transverse bore in the door in which the housing is placed relatively to the door. Thus, the spindle housing S is inserted into a bore in a door as illustrated in Fig. 1, whereupon the rotation of the roses will clamp it relatively to the bore of the door and hold it in central assembled relation thereto.

The outside end of the spindle housing is covered by a decorative brass scalp 17, as can best be seen in Figs. 1 and 4, while the inside end of the spindle housing is covered by a decorative scalp 18, both scalps being forced over the ends of the housing and serving not only as decorative members, but also to hold in assembled relation the two parts 13, 14 forming the spindle housing S.

The outside knob is designated by reference numeral 19 and is here shown formed of sheet metal crimped at opposed points 20 for assembly to a sleeve 21, it being appreciated that because of the particular relationship, the knob and sleeve will always be rotatable together. Because the particular lock described by me here is to be used as an outside lock, there is carried by outside knob 19 a pin tumbler cylinder 22 equipped with a key plug 23 held assembled to the cylinder by a plate 24. Those skilled in the art will appreciate that upon insertion of a key into the key plug 23, the key plug will be rotatable relatively to the cylinder 22 from an initial locked position to a release position. When the key and key plug are rotated back to the initial locked position, the key is then removable, all as is standard and well known in this art.

The inside knob is designated by reference numeral 25 and is also formed of sheet metal. The inside knob carries a push button 26 adapted to operate a plate 28 with friction being applied to the plate by a spring 29 carried by the knob, it being the function of the spring to hold the plate 28 and the push button 26 yieldingly in any position to which the push button may be moved. The sheet metal forming the inside knob is crimped at 30 to a cylindrical member 31 in the same manner as the outside knob 19 is crimped at 20 to the sleeve 21. Therefore, the cylindrical body 31 and the knob 25 will always rotate together.

The cylindrical body 31 carries therein a retainer 32, pressed by a spring 33 in an upward direction as viewed in Figs. 2 and 4. It is the function of this retainer 32 to enter a slot 34 in the spindle 35 best illustrated in Figs. 13 and 14. Thus, when the inside knob is applied to the spindle housing, it enters a bore 36 at the left hand end of the spindle housing seen in Fig. 1 until the detent 32 moves opposite one of the slots 34 of the spindle plate 35. The retainer 32 will move into the particular slot 34 and thereafter will hold the knob 25 against outward movement relatively to the spindle 35 and therefore against movement outwardly of the lock. When it is desired to remove the inside handle, the retainer 32 may be pressed downwardly in Figs. 2 and 4 against the pressure of the spring

33 and out of one of the slots 34. This is accomplished by rotating of the inside knob and the cylindrical body 31 until one end of the retainer is opposite a series of aligned openings 37 formed in the sleeve 18, the spindle housing S and the sheet metal of the knob 25. Of course, upon movement of the retainer 32 downwardly as described, the knob and the cylindrical body 31 may be moved away from assembled relation to the locking mechanism. It will be appreciated that the cylindrical body 31 supports also for movement the part 28 secured to the push button 26, the said part having a lug 26a whereby it also is retained in the body by retainer 32. Further, the cylindrical body 31 serves to unite the inside knob 25 for rotation integrally with spindle 35.

Referring now particularly to Figs. 13 and 14, I shall describe the general manner in which my spindle 35, preferably flat and fabricated from sheet metal, is controlled and actuated. Spindle 35 is slotted at 38 so that a U-shaped spindle detent 39 may be inserted through the slot into the particular assembled relation well shown in the several figures of the drawings. A spring 71 between the parts presses spindle detent to the left of spindle 35 in Fig. 13 as well illustrated. An aligning plate 40 is equipped with a central opening 41, and a series of four slots 42, it being the function of each of the slots 42 to align properly a part of the flat plate-like spindle 35 and a part of the plate-like spindle detent 39. It is, therefore, obvious that the aligning plate 40 will hold the spindle detent 39 and spindle 35 at right angles to one another and for sliding movement of the spindle detent 39 relatively to the spindle 35. Also, the aligning plate 40 functions as a bearing member, it being adapted to rotate with the spindle 35 and the spindle detent 39 relatively to the spindle housing, and lying for that purpose within a slot 43 of the spindle housing best shown in Fig. 13.

A coupler 44 is equipped with cross slots 45 and 46 for housing the inner end portion of the spindle 35 and spindle detent 39 as is probably best seen in Fig. 13, the coupler itself being best illustrated in Fig. 14. A spindle dog 47, well shown in Fig. 14, is moved into place over the coupler 44 so as to ride on the surface 48 of the said coupler as best seen in Fig. 13. Further, the dog 47 is adapted also to be retained in slot 49 formed on the legs of the U-shaped spindle detent 39. The dog 47 is assembled relatively to the coupler 44 and spindle detent 39 as seen in Fig. 13 by the alignment first of its slots 50 with the lugs 51 of the spindle detent 39, after which its rotation to the position of Fig. 14 will remove the slots 50 thereof from opposite the lugs 51. Thereafter, the spindle dog 47 will lie within the slots 49 of spindle detent 39 and will be prevented from endwise movement relatively to the spindle detent 39, and for movement integrally therewith longitudinally of the spindle 35.

It will be noted that when the dog 47 is in the position of Fig. 13 relatively to the spindle 35, its slots 50 are in engagement with surfaces 52 of the spindle 35 so that the dog and spindle 70 are held against relative rotation. It is so held by detent 39 under the influence of spring 71. Therefore, rotation of the dog 47 must effect rotation of the spindle 35 and vice versa. On the other hand, should the dog 47 be moved to the right from its position in Fig. 13 and oppo-

site the neck 53 of the spindle 35, then the dog 47 will be free for rotation relatively to the spindle 35, and similarly the spindle 35 will be free for rotation relatively to the dog 47. Dog 47 is thus moved longitudinally of the spindle 35 by spindle detent 39, it being remembered that the dog 47 must move with spindle detent 39 because it lies within the slots 49 of the spindle detent 39. This movement of the spindle detent 39, and therefore of dog 47 is contributed by the plate 28 moving with push button 26. Thus, whenever the push button 26 is moved from its position of Figs. 1 and 4 to the position of Fig. 6, the spindle detent 39 will be moved to the right and to the position of Fig. 6, thereby effecting movement of the dog 47 to the right relatively to the spindle 35. Dog 37 lies at all times within slot 21s of sleeve 21 fixed to the outside knob but in different longitudinal positions relatively thereto. Moreover, dog 47 can never rotate, once in spindle housing S, out of slots 49 of the spindle detent 39, since both its rotation and the rotation of spindle detent 39 are limited.

When the dog 47 is moved by the action of push button 26 to the position of Fig. 6, it is placed between shoulders 54 formed on the spindle housing portion 14, these shoulders being well illustrated in Fig. 13 and also in Fig. 3. When the dog 47 is in its normal position illustrated in Figs. 1 and 4, it will be just to the left of the shoulders 54, and opposite surface 55 of the spindle housing portion 14 illustrated in Fig. 13. It is obvious, therefore, that when the dog 47 is opposite the surface 55 in the position of the parts in Fig. 1, the dog 47 is free to rotate the spindle and may readily be rotated by the outside knob. On the other hand, when the dog 47 is positioned between the shoulders 54, the dog will be held against rotation.

At the same time that the dog 47 is moved to a locked position between the shoulders 54, it is also moved opposite the neck portion 53 of the spindle 35. Therefore, the spindle 35 will be capable of rotation relatively to the dog 47. Therefore, even though the depression of the push button 26 locks the dog 47 against rotation in the position of the parts in Fig. 6, it still leaves the inside knob 25 free for rotation with the spindle for the retraction of the latchbolt as will presently be described. Naturally, the outside knob, is locked however, together with dog 47 because of the fact that dog 47 lies always in slot 21s of sleeve 21 fixed to the outside knob 19.

The latchbolt housing L has already been set forth as containing a latchbolt 11 and a latchbolt retractor 12. The latchbolt 11 is normally maintained spring pressed outwardly into the position of Figs. 1 and 6 by a spring 56 well illustrated in Figs. 1 and 5. A deadlock controlling plunger is designated by reference numeral 57, and it is pressed outwardly by a spring 58. The manner in which the plunger 57 controls the latchbolt 11 will not be here described as it does not form part of my invention herein to be claimed. Latchbolt 11 is retractable by operation of a walking beam 59 pivoted at 60 to a casting 61 that is inserted into the housing L to form an integral part thereof. Walking beam 59 contacts the latchbolt at 62 and is equipped with a surface 63 in contact with a surface 64 of the retractor 12. It will readily be appreciated that when the retractor 12 is moved from the position of Fig. 5 to the position of Fig. 7, its surface 64 operating against surface 63 of the walking beam

59, will effect retraction of the latchbolt 11 against the pressure of the spring 56. It will also be seen that spring 56 serves to hold the retractor 12 in its position of Fig. 5, wherein the retractor is shown juxtaposed relatively to spindle 35.

For assembling the latchbolt housing to the spindle housing, there is pivoted about the same shaft 60 that carries the walking beam 59 a detent lever 65 urged clockwise in Fig. 5 by a leaf spring 66. The detent lever 65 has a hook portion 67 adapted to co-act with any one of the four retaining lugs 68 formed on the spindle housing S. At this point it will be well to consider that the spindle housing S is formed with opposed openings located centrally thereof and designated by the letter O, the four retaining lugs 68 outlining the opposed openings as is well seen in the drawings. Therefore, it is possible to move the latchbolt housing into that assembled relation to the spindle housing illustrated in Fig. 5 in full lines. It is also possible to turn the latchbolt housing up-side-down and insert it at the opposite side of the spindle housing as illustrated in dash and dotted lines in Fig. 5. As a matter of fact, it is possible thus to insert the latchbolt housing in four different positions relatively to the spindle housing S, it being clear that in each position the end of the retractor 12 will lie in juxtaposed relation to the spindle plate 35 as best seen in Fig. 5.

Because of this relationship of the parts, it is possible to assemble the latchbolt housing to the spindle housing as illustrated in Fig. 16 where the bolt is shown with its bevel placed in one particular relationship to the spindle housing. By merely turning the latchbolt housing 180° in its longitudinal axis, it may be assembled relatively to the spindle housing as shown in Fig. 17 where the bevel of the bolt is directly opposite that illustrated in Fig. 16. On the other hand, the latchbolt housing may be assembled relatively to the upper opening O illustrated in Fig. 16, in either one of two rotated positions so as to yield the assemblies illustrated in Figs. 18 and 19. All this is possible because of the very novel concept of my invention. Of course, in all positions the latchbolt retractor 12 will be operable by the spindle 35, as well illustrated through reference to Figs. 5 and 7.

I have already described just how the spindle detent 39 and dog 47 are moved to the right from their position of Fig. 13 and Fig. 1 to the position of Fig. 6 by action of push button 26. I shall now describe just how the spindle detent and the dog 47 are maintained in the position of Fig. 6. It will be noted that the spindle detent 39 is bevelled at 69. Therefore, in its movement from the position of Fig. 1 to the position of Fig. 6 it cams the retractor 12 slightly downwardly in Fig. 1 until it moves to the right of the retractor 12 as illustrated in Fig. 6. Thereupon, the retractor 12 is held by the latchbolt spring 56 through the walking beam 59, in the position of Fig. 6 and against the surface 16 of the spindle detent 39. Therefore, in the position of the parts in Fig. 6, the retractor 12 locks the spindle detent 39 against movement to the left under the influence of the spring 71 tending normally to move the dog 47 and the spindle detent to the extreme left position relatively to the spindle 35 illustrated in Figs. 1, 4, and 13.

If the inside knob 25 is now rotated, it will rotate spindle 35 integrally therewith because the dog 47 is in release position relatively to the spindle, being opposite the neck portion 53 of the

spindle. This movement of the spindle 35 will effect movement of the retractor 12 from the position of Fig. 5 to the position of Fig. 7. This will, of course, move the retractor 12 away from surface 70 of the spindle detent 39, and the spindle detent 39 will move with the dog 47 under the influence of spring 71 back to the position of Fig. 1. In other words, immediately upon rotation of the inside knob 25, the retractor 12 releases the spindle detent and the dog 47 so that they move to unlocking position.

Let us now say that the inside push button 26 has moved the spindle detent to the position of Fig. 6, rendering the outside knob inoperative to rotate the spindle 35, due to the fact that it is locked against rotation by the dog 47 and due further to the fact that the dog 47 is functionally released from the spindle 35. Means must now be provided so that the outside knob may be rendered operative through the rotation of the key plug 23 already described. Moreover, the rotation of the key plug 23, must as I have already emphasized, not allow for the release movement of the push button 26 to the position of Figs. 1 and 4. In other words, it is desired that the key actuation of the plug 23 merely temporarily render the outside knob 19 operative, but not permit a throw-off of the locked condition created earlier by the inward push of the push button 26.

For the particular purpose, the key plug 23 is formed with a lug 72 lying within opposed slots 73 of a sleeve 74 which I term a dog actuator. This sleeve 74, as best illustrated in Figs. 4, 8, 9, and 10, is formed with opposed cams 75 terminating in a central limit lug 75a. When the push button 26 and the spindle detent 39 are in the position of Figs. 1, 4, and 13, a lug 76 at the extreme right hand end of the spindle detent 39 is maintained to the left of the opposed cams 75 of the dog actuator 74. While the cams are well illustrated in perspective in Fig. 10, their function can also well be appreciated by an examination of Fig. 4 wherein the lug 76 is shown displaced laterally from the cams 75. When the push button 26 is moved inwardly from the position of Fig. 4 to the position of Fig. 6, lug 76 is moved to the right of the cams 75 of the dog actuator 74. If now the dog actuator is rotated by the key plug 23, one or the other of the cams 75 will press against the lug 76 moving the spindle detent further to the right from its position of Figs. 6 and 11. This movement of the spindle detent to the right from the position of Fig. 6 will bring the dog 47 away from opposite the shoulders 54 and into position opposite surface 71 of the spindle housing as best seen in Fig. 12. Therefore, dog 47 will now be free for rotation once again and the outside knob will also be free for rotation and can rotate the dog 47 through the slots 21s.

Moreover, the dog 47 will have moved with the spindle detent to bring its slots 50 into alignment with the portions 78 of the spindle 35, best illustrated in Figs. 13 and 14. Therefore, the dog 47 is once again coupled to the spindle 35 and will rotate that spindle. Because of this relationship of the parts, the outside knob will rotate the dog 47 and spindle 35 and will retract the latchbolt. If, once the latchbolt is retracted to allow opening of the door, the latchbolt is again projected, the mere rotation of the key plug 23 back to its position of Fig. 6 will allow the spindle detent 39 to move also to the position of Figs. 6 and 11, bringing the surface 70 of the spindle detent once again opposite the retractor 12 as illustrated in Fig. 6. Once again the outside knob will be

held locked because dog 47 will have entered between the shoulders 54 of the spindle housing S. At the same time, the dog 47 will have moved opposite the neck portion 53 of the spindle 35 so that the outside knob is locked and is functionally disconnected from the spindle 35. Thus, the release rotation of the key plug to release the outside knob temporarily has not effected a throw-off of the outside knob locking mechanism.

It will be remembered that it is undesirable in one form of lock to release the push button and spindle detent for movement from the position of Fig. 6 to the position of Figs. 1 and 4 when the latchbolt 11 is retracted as by the shutting of a door. My lock operates as is desired in this instance because of the relationship between the surface 70 and the end surface of retractor 12. Thus, it will be appreciated that should the latchbolt be moved inwardly in Fig. 5, there will be no pressure thereafter against the walking beam 59 by surface 62, and there will be nothing to prevent the free movement to the left in Fig. 5 of the retractor 12. Therefore, even very slight pressure exerted endwise against the retractor 12 and toward the left in Fig. 5 or downwardly in Fig. 6, will be effective to move the retractor, because there is nothing but slight friction to oppose such movement of the retractor once the latchbolt has been retracted, as by a strike. The relationship between surface 70 of the spindle detent and the end surface of retractor 12 is such, however, that absolutely no end pressure is exerted against retractor 12, and the retractor functions to hold the spindle detent 39 in its position of Fig. 6 even when the door is closed.

In some instances it is desired to effect release of the spindle detent upon retraction of the latchbolt by a strike. There, it is only necessary to bevel the surface 70 so that it takes the form of the surface 70a in Fig. 21. Now, should the latchbolt be retracted as illustrated in Fig. 21 through closing of the door, there will no longer be any pressure whatsoever on the walking beam 59 nor any pressure at 63, 64 on the retractor 12. Therefore, the spring 71 will press the spindle detent 39 to the left in Fig. 21 and such movement will not be opposed by the retractor 12. Therefore, there will be an automatic release of the push button and the spindle detent 39 by the retraction of the latchbolt through the closing of the door.

Means are provided by me to maintain the spindle in a particular normal position corresponding to that illustrated in Figs. 4, 5, and 6. For the purpose, there is mounted about the spindle 35 and the spindle detent 39 a sleeve 80 that is so slotted as to fit over the spindle and detent and to be rotatable integrally therewith. Mounted about the sleeve 80 is a controlling sleeve 81 and a second controlling sleeve 82, there being a torsion spring 83 positioned between the sleeves so as to rotate the sleeves in opposed directions relatively to the axis of rotation of the spindle 35. Through suitable opposed lugs, the sleeve 80 will rotate one of the controlling sleeves 81 when the spindle rotates in one direction and the other controlling sleeve 82 when the spindle rotates in the reverse direction. The arrangement of the controlling sleeves and the spindle is well set forth in my earlier application, Ser. No. 64,735 filed December 11, 1948, and since it per se is not claimed in this application, it is thought that no further detailed description thereof need be shown here. Obviously, other means could be readily devised for yieldingly resisting the rotation of the spin-

die 35 from its normal position relatively to the spindle housing S.

Those skilled in the art will now appreciate that through my mechanism I contribute a latchbolt and spindle housing assembly adapted for four different operative relationships. Moreover, because of the form of my spindle and spindle detent, the operation of the spindle and spindle detent is the same in all four relationships. It is readily appreciated that I also obtain all those desirable operating relationships that I have heretofore set forth generally, using substantially the same parts, so that my lock is adapted readily for use on a bathroom door, a bedroom door, and an outside door. I consider my invention to be one of extreme importance to this art and a contribution that has long been sought.

I now claim:

1. In a lock of the class described, a spindle housing, a spindle rotatably mounted in said spindle housing, a latchbolt housing, a latchbolt retractor in said housing with a part thereof extending from said latchbolt housing, said spindle housing having opposed openings whereby said latchbolt retractor enters said spindle housing selectively at each of diametrically opposed positions to reverse the operation of the lock and with said retractor and latchbolt housing selectively in either of two opposite positions in each of said diametrically opposed positions, and means on said spindle rotating and thereby moving said retractor in each of the four positions said retractor assumes relatively to said spindle housing.

2. In a lock of the class described, a spindle housing having a transverse through opening, a spindle rotatably mounted in said spindle housing and extending past said transverse opening, a latchbolt housing, a latchbolt retractor in said latchbolt housing with a part thereof adapted for insertion into said spindle housing selectively through each end of said transverse opening and toward said spindle to reverse the operation of the lock, and with said retractor and latchbolt housing selectively in either of two opposite positions as said retractor is thus inserted into each end of said transverse through opening, and means on said spindle rotating and thereby moving said retractor in each of the four positions said retractor assumes relatively to said spindle housing.

3. In a lock of the class described, a spindle housing having a transverse through opening, a spindle rotatably mounted in said spindle housing and extending past said transverse opening, a latchbolt housing, a latchbolt retractor in said latchbolt housing adapted for insertion into said spindle housing selectively through each end of said transverse opening toward said spindle to reverse the operation of the lock, and means on said spindle rotating as said spindle rotates relatively to said spindle housing and thereby moving said retractor in each of the positions said retractor assumes relatively to said spindle housing.

4. In a lock of the class described, a spindle housing, a spindle rotatably mounted in said spindle housing, a latchbolt housing, a latchbolt in said latchbolt housing, a latchbolt retractor in said latchbolt housing, means whereby movement of said latchbolt retractor inwardly of said latchbolt housing retracts said latchbolt, said spindle housing having opposed openings whereby said latchbolt retractor enters said spindle housing selectively at each of diametrically opposed positions to reverse the operation of the lock, and means on said spindle rotating and

thereby moving said retractor inwardly of said latchbolt housing and outwardly of said spindle housing in each of said opposed positions.

5. In a lock of the class described, a spindle housing, a plate mounted for movement in said spindle housing with a latchbolt retracting surface positioned substantially diametrically of said spindle housing, a latchbolt housing, a latchbolt retractor in said latchbolt housing, said spindle housing having an opening whereby said latchbolt retractor enters said spindle housing selectively at each of opposed positions to reverse the operation of the lock, and means moving said plate and its latchbolt retracting surface and thereby moving said retractor in each of the positions said retractor assumes relatively to said spindle housing.

6. In a lock of the class described, a spindle housing, a spindle rotatably mounted in said spindle housing with opposed latchbolt retracting surfaces positioned substantially diametrically of said spindle housing, a latchbolt housing, a latchbolt retractor in said latchbolt housing, said spindle housing having opposed openings whereby said latchbolt retractor enters said spindle housing selectively at each of diametrically opposed positions to reverse the operation of the lock, and said opposed latchbolt retracting surfaces of said spindle rotating and thereby moving said retractor in each of said opposed positions.

7. In a lock of the class described, a spindle housing, a plate-like member mounted for movement in said spindle housing, a latchbolt housing, a latchbolt retractor in said latchbolt housing, said spindle housing having an opening whereby said latchbolt retractor enters said spindle housing selectively at each opposed positions to reverse the operation of the lock, the end of said retractor in said positions lying juxtaposed to one side of said plate-like member, and means on said spindle housing for moving said member and thereby moving said retractor in each of the positions said retractor assumes relatively to said spindle housing.

8. In a lock of the class described, a spindle housing, a plate-like member mounted for movement in said spindle housing, a latchbolt housing, a latchbolt retractor in said latchbolt housing, said spindle housing having an opening whereby said latchbolt retractor enters said spindle housing selectively at each of opposed positions to reverse the operation of the lock, the end of said retractor in said positions lying juxtaposed to one side of said plate-like member, whereby the movement of said plate-like member moves said retractor in each of said opposed positions said retractor assumes relatively to said spindle housing.

9. In a lock of the class described, a spindle housing, a flat plate-like member mounted for movement in said spindle housing, a latchbolt housing, a latchbolt in said latchbolt housing, a latchbolt retractor in said latchbolt housing, means whereby movement of said latchbolt retractor inwardly of said latchbolt housing retracts said latchbolt, said spindle housing having an opening whereby said latchbolt retractor enters said spindle housing selectively at each of opposed positions to reverse the operation of the lock, the end of said retractor in said positions lying juxtaposed to one side of said flat plate-like member, and means in said spindle housing moving said flat plate-like member whereby to move said retractor inwardly of said latchbolt housing and outwardly of said spindle housing

in each of the positions said retractor assumes relatively to said spindle housing.

10. In a lock of the class described, a spindle housing, a flat plate-like member mounted for movement in said spindle housing, a latchbolt housing, a latchbolt in said latchbolt housing, a latchbolt retractor in said latchbolt housing, means whereby movement of said latchbolt retractor inwardly of said latchbolt housing retracts said latchbolt, said spindle housing having an opening whereby said latchbolt retractor enters said spindle housing selectively at each of opposed positions to reverse the operation of the lock, the end of said retractor in said positions lying juxtaposed to one side of said plate-like member, and knobs for moving said member and thereby moving said retractor inwardly of said latchbolt housing and outwardly of said spindle housing in each of said opposed positions.

11. In a lock of the class described, a spindle housing, a plate movably mounted in said spindle housing with a latch bolt retracting surface facing one side of said spindle housing, a latch bolt housing, a latch bolt in said latch bolt housing, a latch bolt retractor in said latch bolt housing, means whereby movement of said latch bolt retractor inwardly of said latch bolt housing retracts said latch bolt, said spindle housing having an opening whereby the end of said latch bolt retractor enters said spindle housing in juxtaposition to said latch bolt retracting surface of said plate, a knob on said spindle housing, and means whereby said knob moves said plate in said spindle housing to retract said latch bolt through coaction of said latch bolt retracting surface with said retractor.

12. In a lock of the class described, a spindle housing, a thin flat plate having a latch bolt retracting surface movably mounted in said spindle housing, a latch bolt housing, means supporting said latch bolt housing relatively to said spindle housing, a latch bolt in said latch bolt housing, a latch bolt retractor in said latch bolt housing having a vertical end surface, means whereby movement of said latch bolt retractor inwardly of such latch bolt housing retracts said latch bolt, a spring holding said plate with its latch bolt retracting surface substantially parallel and juxtaposed to said end surface of said latch bolt retractor, a knob rotatably mounted relatively to said spindle housing, and means whereby said knob moves said plate in said spindle housing against the force of said spring to retract said latch bolt through pressure of said latch bolt retracting surface against the end surface of said retractor.

13. In a lock of the class described, a spindle housing, knobs mounted for rotation relatively to said spindle housing, a plate movably mounted

in said spindle housing, a latchbolt housing, a latchbolt retractor in said latchbolt housing, said spindle housing having an opening whereby said latchbolt retractor enters said spindle housing selectively in each of opposed positions of said latchbolt housing relatively to said spindle housing to reverse the operation of the lock, the end of said latchbolt retractor lying then in juxtaposed relation to said plate, and means whereby said knobs move said plate relatively to said spindle housing and thereby move said retractor to retract said latchbolt in each of said opposed positions of said latchbolt housing relatively to said spindle housing.

14. In a lock of the class described, a spindle housing, a thin plate-like member mounted in said spindle housing for movement relatively thereto, spring means holding said plate-like member in a vertical position when said spindle housing is mounted in predetermined relation to a door, a latchbolt in said latchbolt housing, a latchbolt retractor in said latchbolt housing terminating in a surface held vertically when said latchbolt housing is assembled with said spindle housing in said predetermined relation to a door, means whereby movement of said latchbolt retractor inwardly of said latchbolt housing retracts said latchbolt, said spindle housing having an opening whereby said latchbolt retractor enters said spindle housing selectively and with said surface juxtaposed to said plate-like member in each of opposed positions of said latchbolt housing relatively to said spindle housing, knobs rotatably mounted relatively to said spindle housing, and means actuated by said knobs for moving said plate-like member and thereby moving said retractor inwardly of said latchbolt housing and outwardly of said spindle housing upon rotation of said knobs in each of the positions said retractor assumes relatively to said spindle housing.

FREDERIC K. HEYER.
